UNITED STATES PATENT OFFICE.

EDWARD ROSE, OF MAMARONECK, NEW YORK.

TROLLEY-MOUNT.

1,086,562.

Specification of Letters Patent.

Patented Feb. 10, 1914.

Application filed June 2, 1913. Serial No. 771,190.

To all whom it may concern:

Be it known that I, EDWARD ROSE, a citizen of the United States, residing at Mamaroneck, county of Westchester, State of New York, have invented an Improvement in Trolley-Mounts, of which the following is a specification.

This invention has for its object to provide a trolley pole so constructed that the trolley will be automatically retained in alinement with the wire so that in turning corners, passing onto and off from side tracks, etc., the trolley will be perfectly free to follow all changes in the alinement of the wire without lateral wearing pressure upon either trolley or wire, thereby effecting a great saving in the cost of maintenance, and eliminating the danger of the trolley running off from the wire.

With these and other objects in view I have devised the novel structure which I will now describe, referring to the accompanying drawing forming a part of this specification and using reference characters to indicate the several parts.

Figure 1 is a side elevation of my novel trolley pole as in use; Fig. 2 a plan view corresponding therewith; Fig. 3 an inverted plan view; Fig. 4 a plan view of the crossed arms and carrying plate, the pivot bolt being in section and the pole and extension removed, and Figs. 5 and 6 are plan views corresponding with Fig. 2 illustrating changed positions of the parts corresponding with changes in the alinement of the wire.

10 denotes the pole, the upper end of which is bent to the horizontal plane and carries a hinge member 11.

12 denotes an extension of the pole which lies in the horizontal plane and carries at its inner end a hinge member 13 which is pivoted to the yoke by means of a vertically disposed bolt 14. The bolt extends below the hinge and has pivoted thereon crossed arms 15 which rest upon a carrying plate 16 through which the bolt also passes, the parts being shown as retained in place by a nut 17. The crossed arms are shaped not unlike scissor members and are shown as recessed into each other like scissor members, the end walls of the recesses, indicated by 18, serving as stops to limit the opening movement of the arms. Ropes 19 are attached to the inner ends of the arms, are passed down-

ward through an opening 20 in the carrying plate and are connected together as at 21 so that a single rope passes down to the car platform by which both arms and the pole are manipulated. The carrying plate is provided with an upturned flange 22 provided with a notch 23 which receives the pole and thus holds the plate against movement independently of the pole. At the forward ends of the arms are upturned ends or lugs 24 which lie on opposite sides of extension 12. At the forward end of the extension is a head 25.

26 denotes the trolley which is journaled in a yoke 27 having a shank 28 which extends through head 25 and is free to oscillate therein. The shank is provided with a collar 29 which rests upon the head. Below the head and rigidly secured to the shank is a lever 30 which is adapted to engage either of the lugs 24 on the crossed arms. The portion of shank 28 which passes through the head of the lever is made angular to lock the lever against rotation on the shank and the parts are secured in place by a nut 31 engaging the threaded lower end of the shank.

The operation will be readily understood from Figs. 5 and 6 in connection with Fig. 2. It will be noted that the shank of the trolley yoke is free to oscillate in the head on the extension and the extension itself is free to oscillate in the horizontal plane relatively to the pole. I thus provide for any possible variation in the position of the wire and changes in alinement as in turning corners. The result is that the flanges of the trolley will automatically retain their parallelism with the axis of the wire and thus avoid any tendency of the trolley to run off from the wire in turning corners or taking side tracks and furthermore wear upon the wire and upon the flanges of the trolley is practically eliminated. Should the trolley run off the wire when the parts are in a position approximating the position shown in either Fig. 5 or Fig. 6, a pull upon the rope will cause the lug upon one of the crossed arms to engage the lever, the effect of which will be to swing the lever and trolley into alinement with the extension and the extension into the vertical plane of the pole, as in Fig. 2. As the pull of the rope is now upon the pole, the pole may be manipulated thereby

and the trolley reengaged with the wire in precisely the same manner as with the poles in common use.

Having thus described my invention I claim:

1. The combination with a trolley pole and an extension pivoted thereto, of a trolley yoke pivotally mounted on the extension, a rope and means adapted to be operated by 10 the rope for swinging the yoke and the extension into the vertical plane of the pole.

2. The combination with a trolley pole and an extension pivoted thereto, of a trolley yoke pivotally mounted on the extension, 15 a lever rigidly secured to the shank of the yoke and pivoted crossed arms having lugs engaged by the lever and adapted to engage the extension, whereby the yoke and the extension may be swung into the vertical 20 plane of the pole.

3. The combination with a trolley pole having its upper end bent to the horizontal plane and an extension pivoted thereto and adapted to swing in the horizontal plane, of 25 a trolley yoke pivotally mounted on the extension and means for swinging the yoke and the extension into alignment with the horizontal portion of the pole.

4. The combination with a trolley pole 30 and an extension pivoted thereto, of a trolley yoke pivotally mounted on the extension, a lever rigidly secured to the shank of the yoke, pivoted crossed arms having lugs at their outer ends adapted to be engaged by 35 the lever and to engage the extension, and ropes connected to the inner ends of the arms whereby the yoke and extension may be swung into the vertical plane of the pole.

5. The combination with a trolley pole 40 and an extension pivoted thereto and having a head at its outer end, of a trolley yoke having a shank pivoted in the head, a lever rigidly secured to the shank, pivoted crossed arms having lugs at their outer ends adapted 45 to be engaged by the lever and to engage the extension, and ropes connected to the inner ends of the arms, for the purpose set forth.

6. The combination with a trolley pole 50 having its end bent to the horizontal plane and provided with a hinge member, an extension having a corresponding hinge member, a pair of crossed arms having lugs at their outer ends, a carrying plate on which 55 said arms rest and which is provided with an opening and an upturned flange having a notch which receives the pole, of a pivot bolt passing through the hinge members, the arms and the carrying plate, a lever rigidly 60 secured to the shank of the yoke and engaging the lugs on the arms and ropes connected to the rear ends of the arms and passing through the opening in the carrying plate, whereby the yoke and the extension may be

swung into alignment with the pole and the 65 pole as a whole may be manipulated.

7. The combination with a trolley pole, an extension pivoted thereto, a trolley yoke having a shank pivoted in the outer end of the extension and a lever rigidly secured to 70 the shank, of crossed arms pivoted concentrically with the extension and having lugs engaged by the lever.

8. The combination with a trolley pole and an extension pivoted thereto, of a trolley yoke having a shank pivoted in the outer 75 end of the extension, a lever rigidly secured to the shank, pivoted crossed arms having lugs engaged by the lever and means acting on the arms for swinging the yoke and the 80 extension into the vertical plane of the pole and for manipulating the pole.

9. The combination with a trolley pole and an extension pivoted thereto, of a trolley yoke pivoted in the extension, a lever rigidly secured to the shank of the yoke, pivoted crossed arms having lugs engaged by the lever and means for manipulating the 85 arms, the yoke and the pole.

10. The combination with a trolley pole 90 and an extension pivoted to swing in the horizontal plane, of a trolley yoke pivoted in the extension, a lever rigidly secured to the shank of the yoke, pivoted crossed arms having lugs engaged by the lever and means 95 for manipulating the arms, the yoke and the pole.

11. The combination with a trolley pole, a pivoted extension and a trolley yoke having a shank pivoted in the extension, of a lever rigidly secured to the shank, pivoted crossed arms recessed into each other, the end walls of the recesses serving as stops to limit the outward movement of the arms, lugs on said arms engaged by the lever and 100 means for manipulating the arms, the yoke and the pole.

12. The combination with a trolley pole, a pivoted extension and a trolley yoke having a shank pivoted in the extension, of a lever rigidly secured to the shank, pivoted crossed arms having lugs engaged by the lever, a carrying plate having an opening and 110 ropes connected to the inner ends of the arms and passing through the opening, for 115 the purpose set forth.

13. The combination with a trolley pole, an extension pivoted thereto and a trolley yoke pivoted in the extension and carrying a lever, of crossed arms engaged by the lever. 120

14. The combination with a trolley pole, an extension pivoted thereto and a trolley yoke pivoted in the extension and carrying a lever, of crossed arms engaged by the lever, a carrying plate on which the arms rest and 125 which is provided with an opening and ropes connected to the inner ends of the arms and passing through the opening.

15. The combination with a trolley pole, an extension pivoted thereto in the horizontal plane and a trolley yoke pivoted in the extension and carrying a lever, of crossed arms having lugs engaged by the lever, a carrying plate and ropes connected to the arms and passing through the carrying plate.

16. The combination with a trolley pole and an extension pivoted thereto and adapted to swing in the horizontal plane, of a

trolley yoke pivotally mounted on the extension and manually operated means for swinging the yoke and the extension into the vertical plane of the pole. 15

In testimony whereof I affix my signature in presence of two witnesses.

EDWARD ROSE.
